CABINET FOR A GAS CHROMATOGRAPH OR SIMILAR ARTICLE

Edmund R. Nichols, Media, Pa., assignor to F & M
Scientific Corporation, a corporation of Delaware

Filed Sept. 30, 1963, Ser. No. 76,786

Term of patent 3½ years

(Cl. D16—2)

FIG. 1.

FIG. 2.

FIG. 3.

FIG. 4.

Fig. 5.

FIG. 1 is a front elevational view of a cabinet for a gas chromatograph or similar article, showing my new design;

FIG. 2 is a top plan view;

FIG. 3 is a rear elevational view;

FIG. 4 is a side elevational view, the opposite side being substantially a mirror image thereof; and

FIG. 5 is an exploded front elevational view thereof, with the cover removed.

I claim:

The ornamental design for a cabinet for a gas chromatograph or similar article, as shown and described.
